SKIRT AND TROUSERS HANGER

Frank J. Urban, Toledo, Ohio, assignor to Magic Hanger, Inc., Toledo, Ohio, a corporation of Ohio

Application July 24, 1952, Serial No. 300,609

5 Claims. (Cl. 223—95)

1

This application pertains to skirt and trousers hangers designed for hanging such garments which have generally circular edges such as the waistbands of skirts and trousers and the cuffs of trousers.

The object of this invention is to provide a hanger which may be inserted in the waistband or cuff of a skirt or trousers by a simple one-hand operation, which is resiliently retained in the garment to be supported, which is designed so that garment removing force tends to increase the garment retaining force and which is so designed as to facilitate its being changed in dimensions.

These and more specific objects and advantages and an understanding of the construction by means of which difficulties inherent in most prior art garment hangers are overcome will be more apparent from the specification which follows and from the drawings, in which:

Fig. 1 is a view in elevation of a garment hanger embodying the invention.

Fig. 2 is a fragmentary enlarged view in perspective of certain details of a hanger embodying the invention.

Fig. 3 is an enlarged sectional view taken along the line 3—3 of Fig. 1.

Fig. 4 is a further enlarged detailed vertical sectional view taken on the line 4—4 of Fig. 3.

Most prior art garment hangers, particularly those designed to support trousers or skirts, fall within two general classifications. First among these is the type in which clips or pins are used to mechanically pinch portions of the cloth to secure a firm hold thereon and, secondly, are those in which elements on the hangers are actually inserted into portions of the garments, for example hooks in the cuffs of trousers. These types of prior art hangers have a common fault. First they are usually of a certain size and thus will not operate successfully on garments varying as much in dimensions as the variance between, say, a size 10 skirt and a size 40 skirt. Secondly, hangers designed for supporting skirts are not well designed for supporting trousers and vice versa.

To overcome these objections to most prior art hangers a hanger embodying the invention relies upon resilient force acting perpendicularly to the force tending to remove the garment from the hanger and incorporates means whereby the retaining force is slightly increased if for some reason the garment tends to be torn off the hanger. A hanger embodying the invention thus has a formed wire body incorporating a hook portion 10, generally parallel body members 11 and 12, cross arms 13 and 14 and oppositely directed support arms 15 and 16. This body may be economically formed from a single length of resilient wire. The ends of the support arms 15 and 16 are turned over generally horizontally to form hooks 17 (see Figs. 3 and 4) which are designed to be inserted in any of a plurality of molded openings

2

18 formed in a series in each of a pair of grippers 19.

The wire from which the various elements of the hanger body are formed should be flexible to permit the two body members 11 and 12 to be flexed inwardly toward each other which, because of the cross arms 13 and 14, pulls the two support arms 15 and 16 inwardly lessening the overall distance between the ends of the grippers 19. In order to urge the arms 15 and 16 outwardly, i. e., to separate the body members 11 and 12, a small spiral spring 20 is engaged with a pair of guides 21 which may preferably be molded from a synthetic resinous material and which are identical with each other, being assembled in reverse relation in a hanger embodying the invention. Each of the guides 21 has a tubular portion 22 in which is molded an opening 23 through which a support arm 15 or 16 extends. Each of the guides 21 also has an upper recess 24 into which extends a corner 25 joining a cross arm, for example 13, to its support arm 16. The guides 21 thus are slid over the ends of the support arms 15 and 16 inwardly until the corners 25 between the support arms 15 and 16 and their cross arms 14 and 13 respectively, enter the recesses 24, and the spring 20 is then hooked in small molded openings 26 and urges the two guides 21 toward each other to thrust the support arms 15 and 16 outwardly.

The grippers 19, of which two are necessary in a hanger embodying the invention, are identical, being mounted in reversed position on the ends of support arms 15 and 16. Each of the grippers 19 has an elongated portion 27 and a wing portion 28. The elongated portion 27 has two sets of parallel ribs 29 on one face and 30 on the opposite face. The pairs of ribs 29 and 30 are in line with each other as can best be seen in Fig. 4. The openings 18 extend through the portion 27 into the grooves between the ribs 29 and 30 and are of such size as to receive the end of the hooks 17 on the support arms 15 or 16. As is best seen in Fig. 3, the openings 18 may be flared at the side leading into the ribs 30 to facilitate insertion of the ends of the hooks 17.

The ribs 29 are of sufficient height as to guard the ends of the hooks 17 which protrude therebetween preventing them from snagging on the material from which the garments are constructed.

The ribs 30 are provided with inwardly extending snap ribs 31 which extend toward each other a sufficient distance and are located above the bottom of the grooves between the ribs 30 a sufficient distance such that the wire from which the support arm 15 or 16 is fabricated will snap between and beneath the snap ribs 31. Each of the ribs 30 may have, for example, three snap ribs along its length, the pairs of snap ribs 31 being opposed. Thus when it is desired to change the overall length of a hanger embodying the invention, each of the grippers 19 can be eas-

ily removed from the end of its support arm 15 or 16 by prying on the gripper 19 to remove its support arm 15 or 16 from beneath the snap ribs 31 and then disengaging the hooks 17 from its opening 18 so that the gripper 19 can be replaced at a greater or lesser distance out the support arm 15 or 16.

Each of the grippers 19 has the wing portion 28 which may be provided with a plurality of garment gripping teeth 32 on its outer edge, extending generally perpendicularly to the ribs 29 and 30 and thus generally vertically when the hanger is in its normal position.

It will be observed in Fig. 1 that each of the support arms 15 and 16 is bent upwardly, for example, at the position indicated by the reference numbers 33. As can best be seen at the right in Fig. 1, this establishes a flexure point about which the arm 15 or 16 can bend swinging its end hooks 17 along the arc indicated by the broken line 34 in Fig. 1 and similarly swinging the outer edge of the gripper 19 along the arc indicated by the reference character 35. A hanger embodying the invention is placed in hanger supporting position by squeezing the garment supporting position by squeezing the body members 11 and 12 between the fingers of one hand to pull the support arms 15 and 16 inwardly, the movement being controlled by the guides 21 and the spring 20 being extended. After the arms 15 and 16 have been pulled inwardly a distance such that the overall length between the teeth 32 of the two opposed grippers 19 is less than the distance across the waistband or cuff of the garment being supported, the grippers 19 are inserted into the garment and the body members 11 and 12 released, allowing the spring 20 to contract, thrusting the grippers 19 outwardly into contact with the garment.

When a force acts to pull the garment downwardly off the hanger, for example, if it becomes snagged or otherwise is pulled upon, the first action is to swing the grippers 19 through the arc 35 around the point 33. Inasmuch as the ends of the support arms 15 and 16 are angled upwardly, such swinging motion tends to increase the horizontal maximum dimension between the outer edges of the grippers 19 and thus to more firmly grasp the garment mounted on the hanger. Further force tending to pull the garment off the hanger must extend the spring 20 before the support arms 15 and 16 move inwardly to release the garment. By properly selecting the strength of the spring 20 this force may be controlled so that a garment can be pulled off the hanger without tearing the material from which it is made.

In addition to the operational features of a hanger embodying the invention which have been described, its design and construction facilitate manufacture and assembly and permit the replacement of any portion of the hanger which may be damaged or broken in use. A hanger embodying the invention can be sold in disassembled form, i. e., the main body of wire, a pair of identical grippers 19, a pair of identical guides 21 and a spring 20 can be placed in a unitary package and the purchaser can easily assemble the hanger by following instructions on the package, thus still further reducing the cost of the hanger and keeping the retail sales price lower. Because of this ease of assembly if, for example, the hanger should be dropped or stepped on or otherwise damaged, the purchaser can buy a replacement part, for instance one of the grippers 19 or the slides 21 or even

the main body itself, at a very low cost and can repair the hanger by replacing the broken part.

So far as is known hangers embodying the invention are the first to be produced having any form of mechanism where individual parts are simple to assemble and disassemble permitting the hanger to be repaired by any purchaser.

Having described my invention as embodied in its improved form, I claim:

1. A hanger for skirts and the like comprising, in combination, a hook, laterally spaced downwardly extending body members depending from said hook, cross arms on said spaced body members which arms are oppositely directed inwardly in close parallel planes, support arms extending outwardly oppositely from the lower ends of said cross arms, said support arms having closely parallel sections adjacent their respective cross arms and outwardly extending sections terminating in upwardly inclined generally co-planar end sections, a garment contactor on the end of each of said end sections and a spring connected to both of said cross arms and tending to urge said support arms outwardly.

2. A hanger for skirts and the like that consists in a pair of laterally spaced, generally vertical, co-planar body elements; a common hook element at the upper end and connecting said body elements; a cross arm at the lower end of each of said body elements, said cross arms lying closely adjacent and being oppositely directed inwardly, each of said cross arms terminating at a point generally beneath the other of said body elements; a generally horizontal support arm on the lower end of each of said cross arms, each of said support arms extending generally oppositely to its cross arm and horizontally beyond its associated body element, the sections of said support arms from the junctions with said cross arms to the points generally beneath the junctions of associated cross arms and body elements, lying parallel and closely adjacent; a spring stretched parallel to such sections of said support arms and acting to pull the cross arm-support arm junctions inwardly; and a garment contactor on the end of each of said support arms.

3. In a hanger according to claim 2 the improvement that consists in the support arms having upwardly inclined end sections whereby the normal horizontal dimension between said garment contactors is smaller than the horizontal dimension therebetween when said garment contactors are pulled downwardly tending to straighten said support arms.

4. A hanger according to claim 2 that includes the improvement of cooperating means at the outermost portions of said support arms and on said garment contactors for relative adjustment thereof for adjusting the size of said hanger horizontally for garments of varying size.

5. In a hanger according to claim 2 the improvement that consists in a guide element engageable with the junction points between each of said cross arms and its associated support arm and that slides along the other of said support arms as a guide.
